UNITED STATES PATENT OFFICE.

HANS J. BENTSON, OF MUSKEGON, MICHIGAN, ASSIGNOR TO AUSTIN MACHINERY CORPORATION, OF TOLEDO, OHIO, A CORPORATION OF VIRGINIA.

EXCAVATOR BUCKET.

Application filed July 28, 1924. Serial No. 728,539.

To all whom it may concern:

Be it known that I, HANS J. BENTSON, a citizen of the United States, residing in Muskegon, in the county of Muskegon and State of Michigan, have invented a new and useful Improvement in Excavator Buckets, of which the following is a specification.

My invention relates to excavating buckets, such as are used, for example, upon trenching machines which are provided with an endless series of buckets mounted to travel around a sprocket upon a frame extending rearwardly from the body of the machine and adapted to be disposed in a trench as the same is cut by digging elements on said buckets.

The principal object of the invention is the provision of an extension member provided with improved means for attaching the same to a bucket of this character in order to increase the width of the cut made thereby, said means being adapted to secure the extension in place in such firm and strong manner that it forms practically a continuation of the body itself.

While I have shown the invention in relation to buckets which are provided with digging elements or teeth, it will be evident that it is readily adaptable to ordinary conveyer buckets, or the like, for increasing the capacity thereof when, and only when occasion demands.

Numerous other objects and advantages of the invention will be apparent as it is better understood from the following description, which, taken in connection with the accompanying drawings, discloses a preferred embodiment thereof.

Referring to the drawings,

Figure 1 is an elevational view of the bottom side of an excavator bucket in which my invention is embodied; and

Fig. 2 is an enlarged detail view of one of the extension members, being taken from the front side thereof.

Upon the drawings, illustrating the best manner in which I have contemplated applying the principles of the invention, the reference character 11 indicates the body of an excavator bucket which is of substantially scoop formation and has a forward portion, 12 formed to have teeth 13 secured thereto, which teeth form the regular digging elements of the bucket. They are attached by means of bolts 14 and 15 extending through

slots 16 and 17, respectively, in the teeth and through apertures 18 and 19 formed in the body of the bucket and the forward attaching portion 12 thereof. The portion of the tooth surrounding the slot 17 is countersunk, as indicated at 21, so that the head of the bolt 15 will not interfere with the digging action, and a recess 22 is formed on the front face of each tooth 13, the outer wall of said recess being hooked inwardly, as indicated at 23, and adapted to engage over the front edge of the attaching portion 12 in the bucket. The opposite wall of said recess is disposed in a channel 24 between the body of the bucket and the forward portion 12 thereof on the under side and in this manner the teeth are firmly held in place so that they are rigid with the bucket when the latter is in action. The number of the apertures 18 and 19 may be sufficient to permit the positioning of any number of teeth which may be required or permitted by the dimensions of the bucket.

For the purpose of extending the width of the cut which may be made by the trenching machine with which the buckets 11 are employed, I provide side extensions 25, which are shown attached to the bucket in Fig. 1 of the drawings and one of which is shown in detail in Fig. 2. Said extensions 25 are provided with rounded portions 26 adapted to conform to the contour of the under side of the bucket to which the extensions are attached by means of bolts 27 extending through apertures 28 in the extension members and corresponding apertures in the body of the bucket. Said extension members are each provided with an integral tooth 29, having a cutting edge 31 and a spur 32 adapted to hook over the forward portion 12 of the bucket in the manner of the portions 23 of the teeth 13. Said extension members are provided with attaching walls 33 and 34 at the rear and side, which walls are adapted to have teeth 35 and 36 attached thereto by means of bolts 37 extending through suitable recesses, or slots 38 in the teeth and through apertures 39 and 41 in said walls. The outer teeth 36 are flared outwardly to cutting edges 42 and all the teeth, both on the bucket proper and on the extension members, are adjustable by reason of the bolt slots provided therein. The forward projections, or lugs, 29 on the extension members hold said mem-

bers to the body with a great strength and rigidity and, while I am aware that bucket extensions of different forms have been tried in the past, none, so far as I know, has ever been nearly so effective and satisfactory in service as that which I provide, mainly because of the difficulty of attachment, which is overcome by the use of said lugs 29 formed as shown and described. These 10 lugs successively prevent the loosening or breaking off of the extension members, and it will be noted that they serve the further function of providing an additional digging element.

15 It is thought that the invention and many of its attendant advantages will be understood from the foregoing description, and it will be apparent that various changes may be made in the form, construction and 20 arrangement of the parts, without departing from the spirit and scope of the invention or sacrificing all of its material advantages, the form hereinbefore described being merely a preferred embodiment thereof.

25 I claim:

1. A digging bucket for excavators and the like, comprising a main body having digging elements at the forward edge thereof, and an extension member secured to said body and having a forward projection engaging over said front edge of the body, the extended portion of said extension member being provided with additional digging elements.
- 30 2. A digging bucket for excavators and the like, comprising a main body having digging elements at the forward edge thereof, and an extension member secured to said body and having a forward projection formed with a hooked portion engaging
- 35 40

over said front edge of the body, the extended portion of said extension member being provided with additional digging elements.

3. A digging bucket for excavators and the like, comprising a main body having digging elements at the forward edge thereof, and an extension member secured to said body and having a forward projection formed with a hooked portion engaging 45 over said front edge of the body, the extended portion of said extension member being provided with additional digging elements and said forward projection having a cutting edge and thus itself constituting one 50 of the digging elements.

4. A digging bucket, comprising a main body provided with digging elements at its forward edge, and an extension member having a portion conforming to the contour 55 of said body and adapted to be secured thereto, said member having a retaining flange extending forwardly and engaging over the edge of the bucket and the extended portion of said member being adapted to have additional digging elements secured thereto.

5. A digging bucket, comprising a main body, extension members adapted to be secured to the opposite sides of said body, 60 said members each being formed with an attaching portion conforming to the contour of a side portion of the body and a retaining lug extending forwardly and engaging 65 over the front edge of said body, and detachable digging elements adapted to be secured to the forward edge of said body and to said extension members.

HANS J. BENTSON.
